UNITED STATES PATENT OFFICE.

JACOB S. URDANG, OF CLEVELAND, OHIO, ASSIGNOR OF ONE-THIRD TO WILLIAM H. SCHEINMAN AND ONE-THIRD TO AARON E. ICOVE, BOTH OF CLEVELAND, OHIO.

AUTOMOBILE-SIGNAL.

1,293,990.

Specification of Letters Patent. Patented Feb. 11, 1919.

Application filed February 19, 1916. Serial No. 79,426.

To all whom it may concern:

Be it known that I, JACOB S. URDANG, a subject of the King of England, and residing at Cleveland, in the county of Cuyahoga and State of Ohio, have invented a certain new and useful Improvement in Automobile-Signals, of which the following is a full, clear, and exact description, reference being had to the accompanying drawings.

10 The object of this invention is to provide a simple efficient illuminated signaling device having a movable arm normally carried within a casing and adapted to be projected therefrom to indicate the vehicle is about to stop or turn. A more specific object is to provide for illuminating the signal arm in such a manner that it may serve two advantageous purposes; first, that it may illuminate the signal arm in such a manner 20 as to give the appearance of an extended hand when the arm is projected laterally from the casing and second, when the arm is in its normal position within the casing the lamp for illuminating the arm may

25 illuminate a colored lens carried by the casing. This colored lens is preferably arranged at the rear side of the casing and may take the place of the usual red lamp at the rear of the vehicle, commonly called the 30 "tail" lamp. Another object of the invention is to arrange a second lamp in the same casing adapted to throw light to one side thereof for illuminating the license number.

In carrying out my invention, I provide 35 a hollow casing adapted to receive the signal arm which is pivoted therein, and which is also hollow so that it may conveniently carry the signal lamp and have one or both sides cut out in the form of a hand, the 40 hand-shaped opening being closed by a suitable screen, such as ground glass. I also provide, in the same casing, a compartment for a lamp projecting light to one side thereof. More specific objects are the arrangement of the lamps and casing and signal arm so that the lamps may be protected while being readily accessible; and also the convenient operation of the arm by connection to one of the controlling parts 45 of the vehicle, such for example, as the brake lever, by which the arm may be operated.

50 My invention is hereinafter more fully described in connection with the accom-

panying drawings and its essential characteristics are summarized in the claims.

In the drawings, Figure 1 is a side elevation of my signaling device, showing the signal arm in its extended position in solid lines, and in its normal position in dot and dash lines; Fig. 2 is a vertical transverse section through the same, showing the signal arm in its normal position within the casing; Fig. 3 is a transverse section through the casing and arm, taken substantially on the line 3-3 of Fig. 2; Fig. 4 is a transverse section through the arm itself, taken substantially on the line 4-4 of Fig. 1.

Referring to the drawings by reference numerals, 5 indicates a casing of sheet metal or like material having two side walls 6 and 7 connected at the top and one edge by a wall 8. The casing is provided with a bottom wall 9. The side of the casing opposite the wall 8 is thus left open for substantially its full height.

10 indicates the signal arm shown as comprising a hollow substantially rectangular casing, also preferably of sheet metal or like material, having side walls 11 and 12, carrying outwardly extending trunnions 15, pivoted to the walls 6 and 7 of the casing whereby the arm may swing on these trunnions as a pivoting means from the position shown in Fig. 2 to the position shown in Fig. 1. Attached to the inner edge wall of the arm, at a point normally above the pivot trunnions, is an eye 16 engaged by a corresponding eye on the end of a rod 17, extending downwardly through the bottom of the casing, and provided with a suitable eye 18 at the lower end thereof, to which may be attached the operative connection (not shown) leading from the brake, lever or other controlling part of the vehicle. Such connection need only be arranged to pull downwardly on the arm a distance sufficient to move the eye 16 from the position shown in Fig. 2 to that indicated in Fig. 1, to cause the arm to assume its outstanding position. Upon the return movement of such operative connection, the arm will swing by gravity to its normal position within the casing, drawing upwardly on the rod 17.

Within the arm 10 is mounted an electric lamp 20, preferably red and carried in a

suitable socket 21, shown as positioned by a bracket comprising an integral tongue 22 turned inwardly from the wall 11. This wall 11 is preferably cut away leaving an opening of the shape of an out-stretched human hand, the plate having integral projections 23 between the thumb and several fingers, as shown. This opening is closed by a glass plate 24, preferably having a ground surface so that the light may be more evenly distributed over the hand-shaped opening, and this glass is preferably held in position against the wall 11 by clips indicated at 25.

Suitable wires 26 are shown as leading to the lamp 20, for supplying current thereto. The wire is shown as suitably coiled to provide slack permitting the swinging of the arm without injuring the wire.

When the arm is within the casing, its lamp stand opposite an opening 30 in the side wall 6 of the casing in which is carried a suitable colored lens 32, preferably red, so that it may obviate the use of a separate red lamp at the rear of the vehicle. The lamp 20, being normally lighted whenever darkness makes it desirable or necessary, throws its rays through the glass 24 which is preferably not colored or only slightly colored, and through the red lens, thus notifying any vehicle in the rear of the presence and position of the vehicle carrying my device. If, while driving the vehicle, it is desired to stop or diminish speed for turning a corner, suitable controlling levers are operated, and if the rod 17 is connected with one of such levers, as for example, the brake lever, when the brake is applied, the arm 10 will be projected, as shown. This moves the lamp away from the position where it lights the red lens, to the outstanding position, when a comparatively light colored illuminated hand is then displayed, giving suitable notice, to any drivers in the rear, of the contemplated action of the vehicle.

In order to obtain access to the interior of the arm 10 for replacing the lamp or like purposes, I prefer to close the end of the hollow arm by the cover 34, hinged at 35 and adapted to be secured in its closed position by a suitable hook indicated at 36.

The casing 5 is preferably somewhat wider than the arm 10 to provide convenient space for the operating arm 17 and wires leading to the lamps, as well as to provide for a separate compartment in which may be mounted a second lamp 40. The inner wall of this compartment is formed by a partition 42, extending between the side walls 6 and 7 and upwardly to a transverse portion 44 meeting the lower end of the edge wall 8.

The compartment thus formed opens outwardly at the edge of the casing and is closed by a cover 45, shown as hinged at 46 to the edge wall 8 and adapted to be held in its closed position by a suitable clasp or hook

such as indicated at 48. The cover 45 is provided with an opening opposite the lamp 40, fitted with a suitable glass indicated at 50, whereby the rays of the lamp may be projected to the side of the casing for any suitable purpose, as for example, the illuminating of the license number. The lamp 40 is shown as provided with a socket 51, mounted on the upper wall 44 of the compartment to which leads wires 52, for supplying current to the lamp 40.

From the foregoing description it will be seen that I have provided a signaling device, neat in appearance, efficient in operation and which may be conveniently attached to a vehicle. It is further apparent that when used with an automobile or like vehicle the device may serve a threefold purpose, that of the usual "tail" lamp, that of giving an indication corresponding to the signal of the driver when extending his hand to the side of the vehicle and that of illuminating the license number.

Having thus described my invention what I claim is:

1. In a signaling device for vehicles, the combination of an upright casing having a closed front and back and one edge and open at the other edge, a hollow rectangular signal arm within the casing pivoted thereto near the upper end and having one of its edges adapted to register with and normally closing the open side of the casing, the rear face of the arm being cut out with a contour representative of a human hand, a lamp carried within the hollow arm opposite the cut out portion, a flat translucent screen on the inner side of the rear face of the arm extending across the cut out portion, a lens carried by the rear wall of the casing in position to register with the lamp when the arm is in normal position, and means for swinging the arm.

2. In a signaling device for vehicles, the combination of a casing having an open side, a hollow arm within the casing and of less width than the casing and pivoted to the casing in position to normally stand with one edge of the arm adjacent to the edges of the front and rear walls of the casing, whereby the edge of the arm substantially completes the closure of the casing, an operating member for the arm connected to it some distance back from its pivot, said operating member occupying the space between the arm and the closed edge of the casing and projecting out of the bottom of the casing, there being a compartment within the said space, a lamp within the compartment, and a side window through the inner edge wall of the casing opposite the lamp and adapted to illuminate an adjacent license number.

3. In a signaling device, the combination of a hollow casing rectangular in cross section and having a parallel front and back

and one edge, the rectangular hollow arm pivoted within the casing and having its rear wall cut out to indicate a signal, a lamp secured within the arm behind said cut out portion, said lamp projecting toward the free end of the arm, a hinged plate at the free end of the arm adapted to close it or allow access to the lamp, means for latching the plate in closed position, and mechanism for swinging the arm to carry the signal 10 from within the casing to a point outside of it.

In testimony whereof, I hereunto affix my signature.

JACOB S. URDANG.
